US0D1104476S

(12) **United States Design Patent** (10) **Patent No.:** **US D1,104,476 S**
(45) **Date of Patent:** **** Dec. 9, 2025**

(54) **CASE**

(71) Applicant: **Dyson Technology Limited**, Wiltshire (GB)

(72) Inventors: **Matthew John Bird**, Swindon (GB); **David James Hill**, Bristol (GB); **Howard Shi-How Cheng**, Swindon (GB)

(73) Assignee: **Dyson Technology Limited**, Malmesbury (GB)

(**) Term: **15 Years**

(21) Appl. No.: **29/839,493**

(22) Filed: **May 20, 2022**

(30) **Foreign Application Priority Data**

Nov. 23, 2021 (EM) 001483804-0001

(51) **LOC (15) Cl.** **03-01**

(52) **U.S. Cl.**

USPC **D3/294**

(58) **Field of Classification Search**

Assistant Examiner — Jillian Mazzola

(74) *Attorney, Agent, or Firm* — Tucker Ellis LLP

(57) **CLAIM**

The ornamental design for a case, as shown and described.

DESCRIPTION

FIG. 1 is a perspective view of a case in an open configuration, illustrating our new design;

FIG. 2 is a perspective view of the case in closed configuration;

FIG. 3 is a left side view thereof;

FIG. 4 is a right side view thereof;

FIG. 5 is a bottom view thereof;

FIG. 6 is a top view thereof;

FIG. 7 is a rear view thereof; and,

FIG. 8 is a front view thereof.

The figures contain broken lines that illustrate portions of the case that form no part of the claimed design.

1 Claim, 8 Drawing Sheets
